(57) **CLAIM**

The ornamental design for a cradle device, as shown and described.

DESCRIPTION

FIG. 1 is a front, bottom, right perspective view of the cradle device showing our new design;

FIG. 2 is a right view thereof;

FIG. 3 is a left view thereof;

FIG. 4 is a front view thereof;

FIG. 5 is a back view thereof;

FIG. 6 is a bottom thereof; and,

FIG. 7 is a top thereof.

The broken lines shown in FIGS. 1–7 are included for the purpose of illustrating environmental elements only and form no part of the claimed design.
